UNITED STATES PATENT OFFICE.

GEORGE F. CALLERY, OF OAK PARK, AND RUDOLPH WM. LOTZ, OF CHICAGO, ILLINOIS.

CARTON.

1,415,988.

Specification of Letters Patent. Patented May 16, 1922.

Application filed July 29, 1918. Serial No. 247,109.

To all whom it may concern:

Be it known that we, GEORGE F. CALLERY, of Oak Park, Cook County, Illinois, and RUDOLPH WM. LOTZ, of Chicago, Cook County, Illinois, both citizens of the United States, have invented certain new and useful Improvements in Cartons; and we do hereby declare the following to be a full, clear, and exact description of the invention, such as will enable others skilled in the art to which it appertains to make and use the same.

This invention has for its object to provide an improved paper carton particularly adapted for closure by machines after having been filled with the merchandise to be shipped therein.

Paper cartons are used very extensively in place of wooden boxes for the shipment particularly of relatively light merchandise, such as packages of cereal products and the like, for which purpose they are sufficiently strong besides being lighter and very much cheaper than the wooden receptacles heretofore used.

The cartons are usually received by the shipper in a collapsed form, the top and bottom walls being open. The bottom wall is closed and the overlapping bottom flaps 30 stitched or otherwise firmly secured together prior to filling the carton with merchandise. The top is then closed and, heretofore, has been generally maintained closed by the application of adhesive tape along the meeting or overlapping edges of the several flaps.

More recently a machine has been built which effects closure of the top of the carton when filled with merchandise by means of stitching by the use of the wire staples commonly used in the art of book-binding, the stitching head of the machine being substantially identical with that used for stitching in the book-binding art.

The object of the present invention is, therefore, to provide a carton which is particularly adapted for stitching by machine to effect closure thereof after being filled, and which further provides all the advantages inherent to the ordinary carton at present in use.

The invention consists in the novel features of construction and combinations of parts hereinafter fully described and particularly claimed.

In the accompanying drawings illustrating a suitable embodiment of the invention:

Figure —1— is a perspective view of an open carton constructed in accordance with the invention, showing the same ready to be closed.

Figure —2— is a perspective view of the carton when closed, a part thereof being broken away to expose another part to view.

Figure —3— is a fragmentary detail top plan view of a carton.

Figure —4— is a fragmentary detail section of the same on the line 4—4 of Figure —2—.

In stitching the overlapped parts of the covers of cartons together after the cartons have been filled, it is obviously necessary to insert underneath the overlapped portions of such cover an anvil member which will cooperate with the stitching head to effect clinching of staples driven through the overlapped parts. The covers usually consist of two end-flaps and two side flaps, and ordinarily, in effecting closure, the two end-flaps are first bent down to rest upon the contents of the carton and then the two side flaps are successively bent down upon the end-flaps so as to overlap the same and overlap each other. Closure is preferably effected by securing the overlapping edge portions of the side flaps together as this produces the neatest and most satisfactory package from every point of view.

However, in the art of machine stitching to effect closure of the filled cartons it has been found necessary to vary the usual order in which the flaps are bent down by first folding down one end flap, then one side flap, then the other end flap, and finally the other side flap. The several parts thus overlapped are successively stitched together and the resulting carton while satisfactory from the standpoint of effective closure, presents an undesirable appearance by reason of the peculiar succession of operations resulting in an unusual relative positioning of the several flaps.

One object of our invention is to provide a carton which may be closed in the ordinary manner, but which is at the same time thoroughly well adapted for machine stitching.

To this end the carton 1 is provided with side flaps each consisting of two parts 2 and 3 respectively, they being separated from each other by cutting a slit 4 longitudinally

of the flap from its juncture with the end wall of the box outwardly to a point substantially midway between the ends of the flap. The slit is then projected laterally preferably along the curved line 5 and is then continued from the end of the curved portion of the free edge of the flap in a straight line 6 parallel with the line of the slit 4, but offset laterally therefrom. The slits of the 10 opposite end flaps are respectively right and left so that the portions 3 thereof are opposed to each other. The side flaps 7 and 8 are of ordinary construction and are adapted to overlap each other midway between the 15 side walls of the carton. The width of the free edge portion of the flap members 3 is preferably equal to the depth of the side flap 8.

In closing the carton the portions 2 of the 20 end flaps are first bent down, as indicated in dotted lines in Figure —1—, and the side flap 7 is then folded over upon the same. If desired these parts may now be stitched together by inserting a relatively thin flat anvil 25 member to project underneath the flap portions 2 and flap 7 and driving staples through the several thicknesses of material thus presented. Generally, however, this is not necessary or desirable, and in the construction of the carton in accordance with 30 my invention it is less necessary than in other instances for reasons which will hereinafter appear.

After the flap portions 2 and side flap 7 35 have been bent down, as above described, the portions 3 of the end flaps are bent down and, as will be obvious, the portions bordered by the straight edges 6 and curved edges 5 will overlap the free edge portion of 40 the flap 7. The flap 8 is then bent down to cover and rest upon the portions 3 of the end flaps whereupon the carton is ready for the stitching operation.

In effecting the stitching a relatively thin 45 flat anvil member 9, such as is shown in Figure —4—, is inserted underneath the free edge portion of the side flap 7 and passes over the portions 2 of the end flaps; one side edge of the anvil member will contact with 50 the side edge 4 of each of the portions 3 of the end flaps contiguous to the juncture of the latter with the end walls of the carton. Thus this anvil member will lie beneath the projecting portions 5—6 of the portions 3 of the end flaps and also underneath the overlapping portions of the side flap 8. A row of staples 10 is now driven through the free edge portion of the said flap 8 from end to end of the latter. These staples pass 60 through the flaps 7 and 8 at those points where the projecting portions 5—6 of the flap members 3 do not project through the line of stitching, and where such portions 5—6 project into the stitch-line the staples 65 will be passed through the three thicknesses

of material, thereby securing the flaps 7 and 8 and the end flap portions 3 firmly together. This prevents the end walls of the carton from bulging outwardly under the influence of strains imposed thereon by the 70 load contained in the carton. The closed carton is of usual appearance while being thoroughly reinforced by the stapling to resist strains and stresses against all parts or walls of the same.

It will be observed that the incision 4 does not provide a perceptible opening, nor one which might present a leak for the admission of water in the event the carton is exposed to rain, and it will further be obvious 80 that after closure of the carton has been effected it will not be possible to distort or bulge the cover sufficiently to enable any part of the contents of the carton to be removed by the insertion of a hand into the 85 same.

While we have illustrated and described the preferred embodiment of the invention in the accompanying drawings it will be obvious, of course, that the same is capable of 90 some modification without departing from the invention as defined in the appended claims.

We claim as our invention:

1. A carton having side and end walls respectively and closure flaps hinged to said respective walls, the end flaps being bifurcated to divide the same, the line of bifurcation extending from a point substantially midway between the side edges of said end flaps at their junctions with the end walls to the free ends of said flaps the outer end portions of the slots bifurcating said flaps being laterally offset from the inner end portions thereof, whereby one part of each flap is of greater width at its free end than the other part, the latter being adapted to be overlapped by one of the side flaps and the latter to be partially overlapped by the larger portions of the end flaps, the other side flap adapted to completely overlap the last-named portions of the end-flaps, and the latter and said side flaps adapted to be secured together by a line of stitching extending parallel with and contiguous to the free end of the last-named side flap there being a free way provided between the narrow ended end flaps and the remaining flaps for the insertion of a suitable anvil strip.

2. A carton having four closure flaps including end-flaps each comprising two parts one of which is of greater width at its free end than at its base and the other of which is of less width at its free end than at its base and side flaps adapted to overlap each other, one of the latter adapted to be partially overlapped by the wider portions of the end-flaps and said last-named portions of said end-flaps completely overlapped by the other side-flap, whereby 130

fastening means passed through overlapping end portions of the side flaps will pass through portions of the end flaps and said flaps when closed presenting a free passage for an anvil member for assisting in the clinching of the fastening means.

3. A carton having four closure flaps including end-flaps each comprising two parts one of which is of greater width at its free 10 end than at its base and the other of which is of less width at its free end than at its base, the first-named part of each flap being wider at its free end than the base of the other part and side flaps adapted to overlap 15 each other, one of the latter adapted to be partially overlapped by the wider portions of the end-flaps and said last-named portions of said end-flaps completely overlapped by the other side-flap, whereby fastening means passed through overlapping end portions of the side flaps will pass 20 through portions of the end flaps and said flaps when closed presenting a free passage for an anvil member for assisting in the clinching of the fastening means.

4. A carton having four closure flaps including end-flaps each comprising two parts of equal width at their bases and of respectively different widths at their free ends and 30 side flaps adapted to overlap each other, one of the latter adapted to be partially overlapped by the wider portions of the end-flaps and said last-named portions of said end-flaps completely overlapped by the 35 other side-flap, whereby fastening means

passed through overlapping end portions of the side flaps will pass through portions of the end flaps and said flaps when closed presenting a free passage for an anvil member for assisting in the clinching of the fastening means.

5. A carton having closure flaps including opposed equal side flaps adapted to overlap each other at their free ends, and opposed equal end-flaps, the latter each comprising 45 two parts of equal width at their bases and of respectively different widths at their free ends, the last-named parts substantially equal in width at their free ends to the depth of one of the side flaps and presenting 50 when closed a longitudinal zone for stitching the flaps together and a free way beneath the zone for the insertion of a suitable anvil member.

6. A carton having closure flaps comprising opposed side flaps adapted to overlap each other at their free edge portions and end flaps each comprising two parts adapted to be overlapped by the side flaps, one part of each end flap adapted to overlap the free 55 edge portion of one of said side flaps and be completely overlapped by the other of said side flaps and providing when closed a free passage beneath the overlapped side flaps and the intermediate end flaps for the insertion 60 of a suitable anvil member for assistance in stitching the overlapped flaps together by wire staples.
